UNITED STATES PATENT OFFICE.

NAFEW J. LLOYD, OF BUTTE, MONTANA.

WRAPPING-MACHINE.

1,239,019.

Specification of Letters Patent. Patented Sept. 4, 1917.

Application filed December 5, 1914. Serial No. 875,686.

To all whom it may concern:

Be it known that I, NAFEW J. LLOYD, a citizen of the United States, residing at Butte, in the county of Silver Bow and 5 State of Montana, have invented certain new and useful Improvements in Wrapping-Machines, of which the following is a specification.

My invention relates to new and useful 10 improvements in wrapping machines and more particularly to a machine for wrapping coils, tires or other articles having a hole inside whether round, square or of other configuration.

15 The primary object of the invention is the provision of means for wrapping such articles by machinery where it has been the usual custom to wrap by hand.

20 A further object is the construction of a machine of this character having means for holding the article to be wrapped and also the rolls or spools of wrapping or winding material.

25 A still further object of the invention is the construction of such a machine in which the article being wrapped is automatically fed in position for receiving the wrapping material.

30 Another object of the invention is the provision of means for operating and stopping the several elements of the machine.

With these and other objects in view the invention consists in the novel details 35 of construction and arrangement of parts which will be more clearly understood from the following description and drawings, in which,

Figure 1 is a view in side elevation.

Fig. 2 is a rear view.

40 Fig. 3 is a front view.

In the drawings, the numeral 1 indicates 45 brackets which are adapted to be secured to a wall or other suitable object for holding the several parts of my machine. Secured to the brackets 1 are the metal casings 2 in which are mounted roller bearings 3, the purpose of which will be presently described. Rotatably mounted within the casings 2 and between the rollers 3 are the sectional rings 4 which are hinged, at 5, and connected at the opposite ends by means of U-shaped straps 6, more clearly shown in Fig. 3 of the drawings. A spring controlled latch 7 is connected to the upper strap of 50 the sections and adapted to engage the strap on the opposite section. As is clearly shown

in Fig. 1 of the drawings, the hinges connecting the sections of the rings extend above the outer periphery of said ring for the purpose which will be more clearly set forth later.

Mounted between the sectional rings 4 is a roll 8 of paper and a roll 9 of burlap or other material for wrapping. As is shown by the dotted lines in Fig. 1 of the drawings, the paper is drawn around one side and under the object to be wrapped and the burlap or other material is brought around the opposite side and over the top of the article to be wrapped. The rolls of material 65 are arranged between the rings 4 and mounted upon suitable pintles whereby the material may be replenished when the supply has become exhausted.

70 The object to be wrapped which I will indicate at 19, is adapted to be supported upon sheaves 20 which are mounted in suitable brackets 21 and said article to be wrapped passes through the sectional rings 4, as clearly shown in the drawings. In placing 75 the article in position the latch 7 of the rings 4 is released from the U-shaped strap members and said sections can be swung upon the hinges 5 so that the article may be inserted within the ring. The sections are 80 then swung into position and latched, as shown in the drawings.

85 Pivots mounted between the bearings 22 are the standards 23 in the lower end of which is mounted a shaft 24 carrying a 90 bevel gear 25 which is adapted to mesh with a similar bevel gear 26 carried by one of the sheaves 20. The shaft 23' is carried by the bearings 22 and pivotally receives the lower end of the standards 23. At the upper 95 end of the standards is mounted a shaft 27 carrying a drum or roller 28. A driving belt 29 driven from any suitable source of power passes between the pivot point of the standards and contacts with the shaft 100 24 carrying the bevel gear 25, as shown in dotted lines, Fig. 1, and then passes up over the shaft 27 carrying the drum or roller 28. By means of this driving belt the sheaves 20 are rotated as is also the roll or 105 drum 28. A lever 30 is connected to the standards 23 and a bar 31 is pivotally connected to the bracket 1, as indicated at 32, and is connected to the lever 30, at 33. Secured to the top of the bracket 1 are the 110 projections or guide lugs 34 in which is mounted a sliding bolt 35 which is connect-

2
ed to the bar 31, at 36. As is shown in Fig. 1 of the drawings, this sliding bolt is in such a position whereby it may engage the hinge 5 when in its forwardmost position. A 5 spring 37 is connected to the bar 31 and to any suitable object for normally drawing the bar back and bringing the drum or roller 28 from out of contact with the ring 4.

Having fully described the detailed construction of my device it is thought that the 10 operation will be clearly understood. When it is desired to use the machine the latch 7 is disengaged from the U-shaped strap of the opposite section and the sections of the 15 rings swung upon the hinges 5 thereby opening the sections. The article to be wrapped is then placed upon the sheaves 20 and between the sections of the rings 4. The sections are then swung upon the hinge and the latch again engaged. When the article 20 to be wrapped is thus placed the wrapping material is drawn from the rolls 8 and 9 around the tire, as shown in dotted lines in Fig. 1 and as above described. The driving 25 power is then started so as to operate the belt 20 and by pulling on the lever 30 the drum or roller 28 is brought into contact with the rings 4. By this operation the sliding bolt 35 is drawn away from the rings and the spring 37 placed under tension. 30 The rings 4 being rotated will wrap the article which is held upon the sheaves and the operation of the sheaves will feed the article being wrapped circumferentially. 35 After the article has been wrapped the lever 30 is released and the spring 37 draws the standards 23 back and disengages the drum or roller 28 from the rings. The spring also swings the bar 31 on the pivot 32 there- 40 by forcing the sliding bolt 35 toward the ring and into engagement with the hinges 5, thereby stopping the ring against further rotation. The wrapped article can then be removed from the wrapping rings and from 45 the sheaves.

From the above it will be seen that I have provided a machine simple in construction which is adapted for wrapping articles of various characters and in which the article 50 being wrapped is automatically fed. It will also be seen that I have provided adjustable bearings for the rolls of wrapping material and means for locking said bearings in position with the wrapping rings.

Having fully described my invention 55 what I claim as new and desire to secure by Letters Patent is:-

1. A wrapping machine comprising means for vertically supporting an annular article 60 to be wrapped, means for applying wrapping material to said article and for retaining said article, through the connection established by the wrapping material, in upright vertical position.

65 2. A wrapping machine comprising means

for vertically supporting an annular article to be wrapped, a ring, through the center of which the top of said article is extended, means carried by said ring for wrapping the article, said wrapping material passing from 70 the ring in opposite directions and thereby retaining the article in the center of said ring, and means for rotating said ring.

3. A wrapping machine comprising means for rotatably supporting an annular article 75 to be wrapped, a ring encircling the article, rolls of wrapping material carried by said ring for wrapping said article, said wrapping material passing from the ring in op- 80 posite directions and thereby laterally sup- porting said article at its upper portion, and means for rotating said ring.

4. A wrapping machine comprising rotatable means for vertically supporting an annular article to be wrapped, a ring en- 85 circling the article to be wrapped, a plural- ity of rolls of wrapping material carried by the said ring, the material from the said rollers being extended radially toward the said article and toward opposite sides 90 thereof for connecting the article to the said rollers whereby the material from the rollers may be wound upon the article at the same time preventing movement of the article within the said ring, and means for 95 simultaneously rotating the said ring and the said supporting means.

5. A wrapping machine comprising a plurality of rotatable sheaves for verti- 100 cally supporting an annular article to be wrapped, a support for said sheaves, bear- 105 ings mounted on said support, standards pivotally mounted on said bearings, a shaft carried by said standards, means carried by said shaft and the support for said sheaves for rotating one of said sheaves, a sectional 110 ring encircling the article to be wrapped, rotatable means carried by the upper ends of said standards and engaging said ring, and means connecting said first mentioned 115 means with said rotatable means for impart- 120 ing a rotary motion to said ring.

6. A wrapping machine comprising a plurality of rotatable sheaves for verti- 115 cally supporting an annular article to be wrapped, a support for said sheaves, bear- 120 ings mounted on said support, standards pivotally mounted on said bearings, a shaft carried by said standards, means carried by 125 said shaft and the support for said sheaves for rotating one of said sheaves, a sectional ring encircling the article to be wrapped, rotatable means carried by the upper ends of said standards and engaging said ring, means connecting said first mentioned means 130 with said rotatable means for imparting a rotary motion to said ring, a lever carried by said standards, a sliding bolt disposed in position to engage and disengage said ring, and a bar connecting said lever with said 135

bolt for moving said bolt into and out of engagement with said ring.

7. A wrapping machine comprising a plurality of sheaves for supporting an annular article to be wrapped, supporting brackets for said sheaves, bearings mounted adjacent said supporting brackets, a shaft carried by said bearings, standards pivotally mounted on said shaft, a shaft for driving said sheaves carried by said standards, a drum carried by the upper end of said standards, a ring encircling the article to be wrapped, the edge of said ring contacting with said drum, the upper end of said standards carrying a shaft for supporting said drum, and a driving belt contacting with each of said shafts whereby a rotary motion will be imparted thereto.
8. A wrapping machine comprising a plurality of rotatable sheaves for vertically supporting an annular article to be wrapped, said sheaves receiving the lower portion of the annular article, a ring encircling the upper portion of the article to be wrapped, a plurality of sources of wrapping material carried by the ring, means for rotating the ring whereby the wrapping material will be wrapped on the article and will retain the article in the center of said ring, and means for simultaneously rotating said ring and said sheaves.

9. A wrapping machine comprising rotatable means for vertically supporting an annular article to be wrapped, a sectional ring encircling the article to be wrapped, said section being hinged together at one end, a roll of wrapping material carried by each of said sections, the material from each of said rolls extending radially toward the center of said ring and connected with said article, and means for simultaneously rotating said ring and said rotatable supporting means.

10. A wrapping machine comprising a rotatable support for the article to be wrapped, a ring encircling the article to be wrapped, a support for said ring, a plurality of rolls carried by said support and contacting with the inner and outer periphery of said ring, a pivoted standard having its pivot point disposed adjacent said rotatable support, said standard extending vertically and having its end terminating adjacent the periphery of said ring, a drum carried by the end of said standard and contacting with said ring, a bar pivotally mounted on the support for said ring, a lever carried by said standard and connected to said bar, a bolt slidably mounted on said support and adapted to engage and disengage said ring, said lever adapted to move said drum into and out of engagement with said ring simultaneously with the operation of said bolt.

11. A wrapping machine comprising a

rotatable support for the article to be wrapped, a ring encircling the article to be wrapped, wrapping material carried by the ring, a pivoted standard, a roller carried by said standard and adapted to engage the ring for rotating the same, means carried by the standard for rotating the rotatable support, means for driving the roller and support operating means, and means for bringing the roller into contact with the ring.

12. A wrapping machine comprising a plurality of rotatable sheaves for vertically supporting an annular article to be wrapped, a ring encircling the article to be wrapped, wrapping material carried by said ring, a pivoted standard, a roller carried by said standard and adapted to engage the ring, a sliding bolt mounted adjacent the ring, and means connecting the bolt and pivoted standard for operating the said bolt, the said bolt being moved into engagement with the said ring when the said standard is swung upon its pivot.

13. A wrapping machine comprising a plurality of rotatable sheaves for vertically supporting an annular article to be wrapped, a ring encircling the article to be wrapped, wrapping material carried by said ring, a pivoted standard, a roller carried by said standard and adapted to engage the ring, means for rotating said roller, a sliding bolt mounted adjacent the ring, means connecting the standard and sliding bolt for operating the said bolt, the said bolt being moved into engagement with the said ring when the said standard is swung upon its pivot, and means for adjusting the standard.

14. A wrapping machine comprising a rotatable support for an article to be wrapped, a ring encircling the article to be wrapped, a support for the said ring, a plurality of rolls of wrapping material carried by the ring, a plurality of rollers carried by the said support and contacting with the said ring, the said ring being rotatably supported by the said rollers for permitting free rotary movement thereof, a pivoted standard, a rotatable element carried by the said standard and adapted to be moved into and out of engagement with the said ring, means for imparting rotary motion to the said rotatable support whereby the annular article will be passed through the said ring, a shaft arranged adjacent the said support and adapted to be rotated by the said means, and means connected to the said shaft and adapted to coöperate with the said rotatable elements whereby the said ring will be rotated when the said rotatable element is moved into engagement with the ring.

15. A wrapping machine comprising a semi-circular casing, a plurality of rollers carried by said casing, some of said rollers being disposed at the inner edge of said casing and the remainder of said rollers

- arranged at the outer edge of said casing, a ring encircling the article to be wrapped, said ring consisting of a pair of semi-circular sections hingedly mounted at their meeting ends, a roll of wrapping material carried by each of said sections said ring contacting with the inner and outer rollers whereby said ring will be supported, the strips of material from said rolls adapted to extend from each of said semi-circular sections toward the center of said ring and connected to the article to be wrapped, and means for rotating the ring and the article to be wrapped.
16. A wrapping machine comprising two semi-circular casings, a plurality of rolls carried by said casings, some of said rolls being disposed at the inner edge of said casings and the remainder of said rolls arranged at the outer edge of said casings, 20 a pair of rings encircling the article to be wrapped, said inner and outer rollers of each semi-circular casing adapted to receive and support one of said rings, and a plurality of rolls of wrapping material carried by 25 said rings, said wrapping material passing from said rolls in opposite directions from opposite side of said rings, and means for rotating the rings and the article to be wrapped.
- 30
- In testimony whereof I affix my signature in presence of two witnesses.
